SEAT HAVING ADJUSTABLE BACK

William Glass, London, England

Application October 21, 1933, Serial No. 694,576
In Great Britain October 26, 1932

6 Claims. (Cl. 155—117)

The present invention relates to seats having adjustable backs and is applicable to various types of seats such as folding frame chairs with slung canvas seats, or chairs with fixed side frames for standing upon a floor or other surface and with either slung canvas or upholstered seats. For convenience of description all such will be hereinafter referred to as chairs.

An object of the invention is to provide a construction of chair with back of adjustable inclination and wherein the weight of the person seated in the chair acts to hold the back firmly in the adjusted position. Another object is to provide such a chair which permits of adjustment through a range of inclination of the back by a person seated thereon without rising from the chair. Another object is to provide a folding frame chair of the deck chair type with adjustable back which is practically proof against accidental collapsing when occupied and still another object is to provide a chair of this type which can be very easily folded or erected and which can be folded into a comparatively short length.

In a chair according to the invention a back frame is pivoted, at a point intermediate its ends and preferably towards the lower end, to a part of the frame of the chair, and the lower ends of the back frame when in erected position, or a member or members mounted thereon, bear upon the upper surface of the rear portion of a seat frame pivoted intermediate its front and rear ends of the same part of the frame of the chair at a point somewhat forward of the lower ends of the back in erected position, so that weight applied on the front end of the seat frame will press the rear end upwards against the lower end of the back frame or the said member or members mounted thereon. A flexible seat is connected at its front end in a hinged manner to the front of the seat frame and at its rear end in a similar manner to the back frame, preferably at or near the upper end of the latter.

In order that the invention thus briefly described may be fully understood and carried into practice, and to show how the objects hereinbefore mentioned are attained, it will now be described more fully with reference to the accompanying drawings, which illustrate certain constructional embodiments of the invention.

In these drawings,

Figure 1 is a perspective view of a folding or "deck" chair in one open position.

Figure 2 is a similar view with the chair in another open position.

Figure 3 is a perspective view of the same chair folded up.

Figure 4 is a side view of a chair having fixed side frames and with one side frame removed, the drawing being of a more or less diagrammatic nature.

Figure 5 is a similar view of another construction of chair with fixed side frames.

Figure 6 is a view of a fragment of the side of a frame showing a modified form of recess.

Referring first to Figures 1-3 inclusive, the frame 1, which in an ordinary "deck" chair is relatively long to constitute the back frame as well as the front legs, is made shorter and the side rails of a second frame 2 are pivoted at 3 to the upper or rear ends of the side rails of the frame 1 on the inside thereof. Another frame 4 forming a seat frame member is provided pivoted to the outside of the rails of frame 1 at 5, this frame constituting the back legs and its front having attached to it at 6 the front end of the canvas seat 7, the rear and upper end of which is attached to the upper end of the frame 2 at 8. The lower ends of the side rails of the frame 2 are provided with outwardly projecting supporting members 9 which in the erected position of the chair abut on the upper surface of the seat frame member 4 behind the pivots 5. When the frame 2 is perpendicular to the frame member 4 and within a certain range of deviation from the perpendicular position, the friction between the members 9 and the frame member 4 due to the weight of the person using the chair is sufficient to hold the frame 2 rigidly in the position to which it is adjusted, and within this range the inclination of the back frame 2 can be adjusted by a person seated in the chair by pushing or pulling on the upper end 8. To prevent adjustment in this manner beyond the range at which friction will hold the back in position, the side rails of the frame member 4 are recessed at 10, the ends 11 of the recesses constituting stops to limit the possible movement. The recess 10 may if desired be curved, as designated by 10a to give an improved friction grip throughout the range of adjustment. Between the recess 10 and the pivot 5 each side rail of frame member 4 is provided with a notch 12. With the seat unoccupied the chair can be so adjusted that the members 9 engage the notches 12 to provide a reclining position as shown in Figure 2.

To fold the chair, the top of the back at 8 is gripped by one hand and lifted to clear the members 9 from the top of the frame member 4, the top 8 is then carried over in the direction of the

arrow on Figure 1 and the whole folded on to the ground and the folded chair can then be picked up with the same hand by grasping the then adjacent front ends of the three frames 1, 2 and 4. 5 The chair in folded position is shown in Figure 3.

The chair can also be erected from the folded and carried position by the employment of only the one hand by a reversal of the operations just mentioned.

10 The chair described has many points of advantage. Within the range of adjustment provided by the recesses 10 the back is held very firmly in the adjusted position by friction due to the weight of the person seated in the chair and nevertheless 15 adjustment can be effected by the person seated without leaving the chair. Accidental collapsing from the reclining position (Figure 2) when the chair is occupied is impossible as even if the notches 12 were absent the members 9 would be 20 locked between the frames 1 and 4. When folded up as shown in Figure 3 the length is very much less than in the case of an ordinary deck chair in which a frame such as 1 is continued to form the back frame. The folded chair is thus much more 25 convenient to carry.

The upper surfaces of the recesses 10 may if desired be roughened to provide an improved friction grip.

30 Obviously the order of the frames 2, 1, and member 4 may be varied in respect of which is the inner one, which the outer one, and which the middle one. Thus frame 2 may be made the outer one, frame 1 the middle one and frame member 4 the inner one. The projections 9 would 35 then be on the inside of the side rails of frame 2 and might be constituted by a continuous bar between the two side rails.

Figure 4 illustrates a chair having fixed side frames 13. The seat frame member 4 is pivoted 40 to these side frames at 5 and the back frame 2 is pivoted thereto at 3. A canvas seat is slung between the upper end 8 of the back frame 2 and the front end 6 of the seat frame member 4. Recesses 10 and notches 12 are provided in the seat 45 frame member to provide for a range of adjustments similar to those described in respect of the deck chair illustrated in Figures 1 and 2, and as the sides of the seat frame member 4 and of the back frame 2 are conveniently in the same plane 50 the members 9 of Figures 1-3 are dispensed with and the lower ends 9a of the sides of the back frame bear directly on the upper surface of the sides of the seat frame member. As in the case 55 of the deck chair described above, the weight of the person seated tends to tilt the seat frame member about the pivot 5 and raise the rear portion of the said frame member towards the pivot 3, thus providing a friction grip between the lower ends 9a of the sides of the back frame and the 60 upper surface of the sides of the seat frame member. The construction permits of the forward folding of the back by first raising the front of the seat frame member. Stops indicated at 16 may if desired be provided to limit the possible 65 movement of the seat frame member when the back is disengaged therefrom and folded forwards.

Figure 5 illustrates a chair which is very similar to that shown in Figure 4. In place of the canvas seat however an upholstered seat is provided formed in two portions 7a and 7b connected together in a hinged manner at 15. The front of the portion 7b is connected in a hinged manner to the front of the seat frame member at 6 and the top of the portion 7a is similarly connected to the top of the back frame at 8. 5

I claim:—

10 1. A foldable chair with adjustable back, comprising a back frame and a seat frame member, wherein the back frame is pivoted, at a point intermediate its ends and preferably towards the lower end, to a part of the frame of the chair and the lower end of the back frame when in erected position bears upon the bottoms of elongated recesses provided on the upper surface of the rear portion of the seat frame member which is pivoted intermediate its front and rear ends 15 to the same said part of the frame of the chair at a point somewhat forward of the lower end of the back frame in erected position, the ends of the said recesses constituting shoulders limiting the backward and forward adjustment of the 20 lower end of the back frame, and wherein a flexible seat is connected at its front end in a hinged manner to the front end of the seat frame member and at its rear end in a similar manner to the back frame, preferably at or near the upper 25 end of the latter. 30

2. A foldable chair according to claim 1, wherein in the bottoms of the said elongated recesses are curved to give an improved friction grip throughout the range of adjustment of the back frame. 35

3. A construction of chair according to claim 1, in which the seat frame member is adapted to contact with the ground at its rear end and also the forward part of the frame to which the back frame and the seat frame member are pivoted. 40

4. A construction of chair according to claim 1, in which the part of the frame of the chair to which the back frame and seat frame member are pivoted, comprises rigid side frames adapted to rest on the ground and to form the sole support 45 of the chair. 50

5. A construction of chair according to claim 1, wherein the bottoms of the said elongated recesses are curved to give an improved friction grip throughout the range of adjustment of the back frame, and the seat frame member is adapted to contact with the ground at its rear end and also the forward part of the frame to which the back frame and the seat frame member are pivoted. 55

6. A construction of chair according to claim 1, wherein the bottoms of the said elongated recesses are curved to give an improved friction grip throughout the range of adjustment of the back frame, and the part of the frame of the chair to which the back frame and seat frame member are pivoted comprises rigid side frames adapted to rest on the ground and to form the sole support of the chair. 60
